UNITED STATES PATENT OFFICE.

ALLEN DE VILBISS, JR., OF TOLEDO, OHIO, ASSIGNOR TO THE TOLEDO
SCALE & CASH REGISTER COMPANY, OF TOLEDO, OHIO, A CORPO-
RATION OF OHIO.

SCALE.

No. 841,254.

Specification of Letters Patent.

Patented Jan. 22, 1907.

Application filed January 25, 1902. Serial No. 51,189.

To all whom it may concern:

Be it known that I, ALLEN DE VILBISS, JR., a citizen of the United States, residing at Toledo, in the county of Lucas and State of Ohio, have invented a certain new and useful Improvement in Scales, of which the following is a description, reference being had to the accompanying drawings, forming part of this specification.

10 My invention relates to what are commonly known as "two-point" bearing-scales, as distinguished from what are known as "four-point" scales—that is to say, scales in which the weighing-platform is supported upon the scale-beam at two points only, as distinguished from scales in which the weighing-platform is supported upon the scale-beam or the lever mechanism connected therewith at four points; and it has for its object the provision of a novel weighing-platform for such scales which will insure the accurate weighing of any article placed upon said platform at any point upon its weighing-surface.

25 Two-point bearing-scales of the character above referred to are illustrated in a number of patents heretofore granted to me, of which it will suffice to refer to No. 649,915, dated May 22, 1900, while a four-point scale, such 30 as referred to, is illustrated in my prior patent, No. 655,147, dated July 31, 1900.

In the accompanying drawings, Figure 1 is a front elevation of a portion of a two-point bearing-scale, showing the scale-beam and 35 my novel weighing-platform supported thereon; Fig. 2, a cross-section approximately on the line 2 2 of Fig. 1; Fig. 3, a cross-section on the line 3 3 of Fig. 2; Fig. 4, a top view of the platform-supporting frame or spider, 40 and Fig. 5 a perspective view of the weighing-platform detached.

The same letters of reference are used to indicate corresponding parts in the several views.

45 A represents the scale-base, rising from which are two arms B B, upon which is fulcrumed the scale-beam C, said beam having knife-edge trunnions a projecting from its opposite sides and resting in bearings in the upper ends of the arms B. Mounted upon the scale-beam C at the left of its fulcrum-support is the platform-supporting frame or spider D, which is provided upon opposite sides of the scale-beam with depending arms b, having

55 bearings resting upon a second pair of knife-edges c projecting from the opposite sides of the scale-beam. Rigidly secured to and depending from the center of the frame D is a rod E, whose lower end is pivoted to the left-hand end of a link F within the scale-base A, 60 as usual. The frame D which supports the weighing-platform G is provided with four supporting-arms d, radiating from the center of the frame to the four corners of the platform, Fig. 4, and the latter rests at its four 65 corners upon the outer ends of said arms.

In scales of this character the entire upper surface of the platform has usually been flat and its whole area utilized as the weighing-surface, upon any part of which the article or commodity to be weighed might be or was liable to be placed. When, however, such article happened to be placed upon the platform adjacent any one of its four corners instead of being placed upon the central portion of the platform it frequently occurred 70 that the scale would not correctly indicate the weight of such article. This defect was due to the fact that the weighing-surface of the platform extended at its four corners to 75 such a distance from the center of the platform-supporting frame D (mounted at only two points upon the scale-beam) that the weight of an article placed upon the platform adjacent any one of the four corners would 80 tend to tilt the supporting-frame and subject it to a torsional strain instead of acting directly upon the scale-beam. It is highly desirable and, indeed, frequently required by 85 law or city ordinances that a platform-scale shall weigh with accuracy any article placed upon any portion of its weighing-surface, so that mistakes may not occur by careless placing of articles upon it or deception be 90 practiced by designedly placing them upon it in such a way as to inaccurately indicate 95 their weight. I have overcome the defect in previous scales of this character which has been above described by contracting the weighing-surface of the platform and bringing it centrally within the borders of the platform and preferably within the points at which the latter rests upon its supporting-frame, so that the articles to be weighed must of necessity be placed upon the platform in such 100 position that they will be accurately weighed. To this end I have in the present instance provided the rectangular platform G with a

2
raised weighing-surface G', having an oval periphery considerably within the rectangular area of the platform proper, particularly at the corners of the latter. The surface of the platform slopes away from the base of this weighing-surface toward the rectangular edge of the platform, so that there is no danger of any one carelessly placing the article to be weighed elsewhere than upon the proper weighing-surface, while it is difficult to designedly do so, particularly without detection, and when placed anywhere upon the weighing-surface G' the supporting-frame will be subjected to no tilting strain sufficient to interfere with the accurate weighing of the article. The weighing-surface G' is substantially flat, being very slightly concaved in the present instance.

It is of course not essential that the weighing-surface G' shall be oval in shape, and if the entire platform were square instead of being of oblong rectangular shape the weighing-surface would naturally be made circular; but it may be square or of other rectangular or irregular shape.

In the present instance the platform G and the raised weighing-surface G' are stamped from sheet metal, the platform being provided with a narrow depending flange e around its edge to engage the arms of the supporting-frame and prevent displacement of the platform therefrom, and the upper surface of the entire platform is covered with an enamel finish.

Having thus fully described my invention, I claim:-

1. A scale-platform provided with a weighing-surface surrounded by a marginal portion, said portion being so inclined as to constitute a non-weighing surface.

2. A rectangular scale-platform provided with a central raised weighing-surface having a curved periphery and a depressed marginal

portion surrounding the same and so inclining away therefrom as to constitute a non-weighing surface; substantially as described.

3. In a scale, the combination, with the scale-beam and the platform-supporting frame mounted at two points thereon, of a weighing-platform supported upon said frame and provided with a raised weighing-surface occupying a portion only of the area of said platform within a surrounding marginal portion thereof so inclined as to constitute a non-weighing surface; substantially as described.

4. In a scale, the combination, with the scale-beam and a platform-supporting frame mounted at two points thereon, of a weighing-platform supported upon said frame and provided with a raised weighing-surface and a depressed marginal portion inclining outwardly and downwardly from the raised weighing-surface and surrounding the same its inclination being such as to make it constitute a non-weighing surface; substantially as described.

5. In a scale, the combination with the scale-beam and the platform-supporting frame mounted at two points thereon and provided with four supporting-arms radiating from its center toward the four corners of the platform, of a rectangular weighing-platform mounted at its four corners upon said arms and provided with a raised weighing-surface having an oval periphery located within the rectangular area of the platform within its points of support upon said frame the portion of said platform surrounding said raised surface being so inclined as to constitute a non-weighing surface; substantially as described.

ALLEN DE VILBISS, JR.
